UNITED STATES PATENT OFFICE.

ALBRECHT HEIL, OF FRANKFORT-ON-THE-MAIN, GERMANY, ASSIGNOR TO
A. WOLF, JR., & CO., OF FRANKFORT-ON-THE-MAIN, GERMANY, A FIRM.

THERMO-ELECTRIC PILE.

SPECIFICATION forming part of Letters Patent No. 715,265, dated December 9, 1902.

Application filed April 22, 1902. Serial No. 104,190. (No model.)

To all whom it may concern:

Be it known that I, ALBRECHT HEIL, a subject of the German Emperor, residing and having my post-office address at 3 Roth-schildsallee, Frankfort-on-the-Main, Germany, have invented certain new and useful Improvements in Thermo-Electric Piles, of which the following is a specification.

The present invention has for its object the construction of a thermo-electrical pile which distinguishes itself advantageously from similar piles hitherto in use by its considerably increased efficiency, its enormous constancy, and the short time it requires for heating.

15 In the subjoined drawings, Figure I represents a side view of a couple or element connected to the cooling-plate *a*. Fig. II shows a front view of three couples connected in series. Figs. III and IV represent a different constructional example of a couple and the arrangement of the working flame.

Each couple comprises, on the one hand, the quite particularly shaped strap *b*, which may consist of a nickel alloy, and, on the other hand, of the block *c*, cast of an antimony alloy. On one of its ends the strap *b* is of one casting with the block *c*. For a short distance it runs first horizontally, afterward upward, and finally for a long distance backward again below the block *c* and beyond same. This special form of the strap *b* is due to the necessity to make the most advantageous possible use of the working flame burning below its perpendicular part. A direct transmission of heat takes place on the short horizontal and on the neighboring perpendicular part of the strap *b*, thence indirectly through its end cast into the block *c*, to the junction and to the block *c*. In the horizontally-conducted long top part of the strap *b* necessary cooling takes place partly through irradiation and partly through the deviation produced by a copper strip *d* soldered to the cold end.

45 The block *c*, with the strap *b*, is soldered to a perfectly-isolated vertical sheet of copper *a*, which is directed parallel to the direction of the outer air streaming toward the flame, and which sheet of copper serves the couples as a cooling appliance and as a bearer.

Figs. III and IV represent a special composition of a couple granting a greater and more complete utilization of the heat of the flame. The short horizontal (under certain circumstances also the perpendicular) part 55 of the strap *b*, the heat-conducting power of which is relatively small, is replaced by a metal piece of very good conductivity for heat. For such purpose a short silver strap is very suitable, which strap is molten on one 60 end to the strap *b* and on the other to the block *c*, but at any rate in such a manner that it produces an intimate and organic connection of the two thermo-electrically effective bodies *b* and *c*. The transmitter *f*, heated 65 by the working flame *e*, is a good conductor of heat and takes up heat, owing to its large surface and its reduced volume, and delivers it continually to the two effective bodies *b* and *c* connected to it, which bodies are thus 70 amply and uniformly heated without their junction being directly exposed to the working flame and the more easily fusible body exposed to the danger of melting off at the junction.

I may suggest that silver or copper alloys of great heat-conducting power, or silver-plated copper strips may be substituted to pure silver strips without altering the principle of the present invention of a heat-transmitter. 80 Instead of with silver the copper strip may also be plated with gold.

What I claim as my invention, and desire to secure by Letters Patent, is—

1. A thermo-electric element or couple comprising a block, a strap connected to the block extending horizontally then upward and backward and over the block, and a strip connected to the extended end of said strap, substantially as described. 85

2. A thermo-electric element or couple comprising a block, a strap connected to the block and bent to extend upward and over the block, a strip connected to the extended end of the strap and a sheet connected to the strip, substantially as described. 90

3. A thermo-electric element or couple comprising a block, a strap connected to the block and extending upward and over the block, a strip connected to the extended end of the 95 sheet. 100

strap and a sheet supporting the block and connected to the strip, substantially as described.

4. A thermo-electric element or couple comprising a block and a strip connected to the block, a sheet arranged parallel to the plane of the couple supporting the block and connected to the strap, substantially as described.

5. A thermo-electric couple comprising a block, a strap, a heat-transmitter, both ends being connected to the warm ends of the couple and adapted to be exposed to the source of heat, substantially as described.

6. A thermo-electric element or couple comprising a block of antimony alloy, a strap of nickel alloy, one of its ends being cast to the block and being bent to extend upward and

backward over the block, and a strip connected to the extended end of said strap substantially as described.

7. A thermo-electric element or couple comprising a cooling supporting-plate, a block mounted thereon, a strap, one of its ends being connected to the block and extending upward and over the block, and a strip connecting the cooling-plate with the extended end of the strap, substantially as described.

In testimony whereof I have signed my name to this specification in the presence of two subscribing witnesses.

ALBRECHT HEIL.
